CLAIM

The ornamental design for an eyeglass case, as shown and described.

DESCRIPTION

FIG. 1 is a front isometric view of an eyeglass case shown in a closed configuration;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and

FIG. 7 is a bottom plan view thereof.

FIG. 8 is a front isometric view of the eyeglass case of FIG. 1 shown in an open configuration;

FIG. 9 is a front elevation view thereof;

FIG. 10 is a rear elevation view thereof;

FIG. 11 is a left-side elevation view thereof;

FIG. 12 is a right-side elevation view thereof;

FIG. 13 is a top plan view thereof; and,

FIG. 14 is a bottom plan view thereof.

The broken line showing of the eyeglass case is for the purpose of illustrating portions of the eyeglass case and forms no part of the claimed design.

1 Claim, 9 Drawing Sheets
